UNITED STATES PATENT OFFICE.

FRANCIS PETELER, OF MINNEAPOLIS, MINNESOTA.

HEATING-FURNACE.

SPECIFICATION forming part of Letters Patent No. 593,492, dated November 9, 1897.

Application filed February 8, 1897. Serial No. 621,884. (No model.)

To all whom it may concern:

Be it known that I, FRANCIS PETELER, of Minneapolis, county of Hennepin, State of Minnesota, have invented certain new and 5 useful Improvements in Heating-Furnaces, of which the following is a specification.

This invention relates to improvements in furnaces for heating purposes, and such as are adapted for use in dwelling-houses, 10 churches, school-houses, and other buildings, whether large or small.

The objects I have in view are to provide a furnace that is simple in construction and therefore inexpensive to manufacture, to provide 15 means for increasing the heating capacity of a furnace without increasing its size, to provide a furnace in which all the heating-surface is within reach of the flames and products of combustion, even when there is 20 only a small fire on the grate; further, to provide means whereby the horizontal smoke and heating pipes may be readily cleaned, and, further, to provide means whereby the substantially upright air-tubes may be cleaned 25 and the ashes and dust that have accumulated upon them dropped into the ash-pan.

To these ends the invention consists generally in the constructions and combinations hereinafter described, and particularly pointed out in the claims.

In the accompanying drawings, forming part of this specification, Figure 1 is a front elevation of a furnace constructed in accordance with my invention, the outer shell or inner closing casing being removed. Fig. 2 is a 35 transverse vertical section of the same. Fig. 3 is a longitudinal vertical section showing also the outer casing of the furnace. Fig. 4 is a plan view of the furnace with the outer casing removed. Fig. 5 is a sectional view 40 on the line $x x$ of Fig. 3.

In the drawings, 1 represents the foundation or bottom of the furnace, which consists of rows of brick preferably laid directly upon 45 the cement or other floor of the basement or room where the furnace is located. The floor of the basement forms the bottom of the ash-pit.

2 represents upright plates forming the 50 back and side walls of the ash-pit and supported upon the foundation 1. These plates

may be secured together by rods or bolts or in any other suitable manner.

At the front of the furnace I provide a suitable casting 3, forming the door-frame, 55 which is bolted to the furnace-jacket and is provided with openings over which are arranged the ash-pit door 4 and the fuel-door 5. These doors are of any preferred construction and are preferably provided with 60 openings and with slides 6 and 7, arranged to cover said openings, as shown in Fig. 1. I prefer to provide in connection with the slide of the ash-pit door a suitable bell-crank-operating lever 8, and to this may be connected a 65 suitable chain or wire 9, by which the slide may be operated for regulating the draft of the furnace. This chain or wire 9 may be arranged so that all the dampers in the furnace and in the cold-air-inlet pipe can be regulated 70 from the first floor of the dwelling.

Arranged upon the walls 2 of the ash-pit is a plate 10, preferably of cast-iron and provided with a flange 11 to engage the upper edge of the walls 2 of the ash-pit, and thereby 75 making a tight joint. The plate 10 is provided with a large central opening, beneath which is arranged the grate 12. The grate 12 consists of a rectangular frame provided with a number of grate-bars, preferably formed integrally with the frame and parallel with the sides thereof. The grate is supported upon suitable rolls 13, mounted in a bracket 14, secured by bolts to the under side of the base-plate 10. Said bracket is also provided with 80 rollers 15, that are mounted upon vertical axes and which bear upon the edges of the grate 12, and thus keep the same in its proper position, but at the same time permit its free movement during the process of shaking. A 85 rod 16 is connected to the grate 12 in any suitable manner and extends through the casting 19 and the door-frame 3 and is adapted to be engaged by an upright shaker-rod 17, as shown in Fig. 3. The lower end of the 90 rod 17 is inserted into an opening in the end of a bar 18, which is secured to the lower side of the casting 19, as shown in Fig. 3. By 95 this means the grate may be rapidly moved back and forth for the purpose of shaking 100 down the ashes, which drop through the grate into the ash-pit. The casting or frame 19

forms the front of the ash-pit and is provided with the flanged projection 19', which extends across the space between the front of the ash-pit and the door-frame 3 and is securely bolted to a lip or flange 19", provided on the inner surface of said frame, as shown in Fig. 3. This casting 19 surrounds the lower opening in the door-frame and prevents any gas from passing down through the ash-pit into the space between the jacket and the inner casing of the furnace. A casting or frame 20 surrounds the upper or fuel door opening in the frame and its outer end is bolted to the inner surface of the door-frame, while its inner end is provided with a flange 21, that is bolted to a flange 22 upon the base-plate 10 and also to the plate 23, forming a portion of the inner casing of the furnace, as hereinafter described. This front plate 23 is of nearly triangular form and rests upon and is secured to the base-plate 10 and is provided with a large opening opposite the fuel-door and with two small openings upon either side of the large opening to receive the hot-air pipes provided on the front of the fire-pot. A plate 24, of the same shape as the plate 23, forms the rear wall of the combustion-chamber of the furnace, its lower end being secured to a flange 25 upon the base-plate 10 and provided with an opening to receive the cold-air pipe on the rear wall of the fire-pot. At each side of the combustion-chamber and supported upon and secured to the base-plate 10 is a substantially rectangular drum 26. Each of these drums is open upon its inner sides, the edges of the front and back walls of the drums being secured by bolts 27 to the front and back plates 23 and 24.

The drums 26 are preferably formed of sheet metal, provided, however, with cast-metal heads 27', that are provided with flanges 28, which are riveted to the walls of the drum. The heads 27' are each provided with a series of flanged openings in which are secured the air tubes or flues 29. These flues extend through the drum and open at their upper and lower ends into the space between the walls of the furnace proper and the outer casing hereinafter referred to. These air-tubes are preferably arranged in two series in each drum, there being, as shown in Fig. 4, five tubes in the first or the series nearest the fire and four tubes in the second, and the tubes being so arranged that those of one series stand opposite the spaces between the tubes of the other series, so that the products of combustion are obstructed and compelled to pass around the tubes of each series. Each drum is provided near the upper part of its outer wall with an opening and a flanged collar 30, fitting said opening and adapted to receive another collar 31 upon a horizontal smoke-pipe 32. These smoke-pipes 32, as shown in Fig. 4, extend back of the furnace and through its outer casing, and the open end of each pipe is provided with a remov-

able cap 33 to permit the cleaning of the horizontal pipes 32. A damper 34 is preferably arranged in each pipe 32, said dampers being connected by chains 35, and another chain may be provided leading to the first floor of the dwelling for the purpose heretofore described. Pipes 36, connected to the smoke-pipes 32, lead to a suitable smoke-pipe 37, that is connected with the chimney.

The upper ends of the drums 26 preferably do not meet and are provided on their inner edges with suitable flanges 40. A plate 38 is supported by the flanges 40 and covers the opening between the upper end of the drums. A filling of fire-clay mortar 39 is placed over the top of a plate 38 and prevents the escape of gas. The lower end of the drum 26, which rests upon the edge of the base-plate 10, forms a tight joint therewith, thereby preventing the leakage of gas. I prefer to arrange the drums over the fire at the angle shown in Fig. 2, though I do not confine myself to this exact angle.

The fire-pot consists, preferably, of a hollow casting 41, resting upon the base-plate 10 and extending around three sides of the grate-opening in said base-plate. This fire-pot may be made in three sections securely bolted together, as shown in Fig. 5. The rear wall of said fire-pot is provided with a cold-air pipe 42, that projects through the inner casing 24 and through which the cold air passes to the interior of the fire-pot. The forward ends of the fire-pot 41 are provided with the hollow projections or pipes 43, (indicated by dotted lines in Figs. 1 and 3 and shown clearly in Fig. 5,) and these projections extend through the inner casing 23 and into the space between the casing 23 and the outer casing or jacket of the furnace. I find that by passing a current of air through the fire-pot in this way that I can add very materially to the heating capacity of the furnace and at the same time prevent the fire-pot from burning out even when subjected to an intense heat. As shown in Fig. 2, I prefer to make the inner wall of the fire-pot next to the fire considerably thicker than the outer wall. The fire-pot is also preferably provided upon its inner wall with a series of small holes 44, and above such holes I form lips 45, which prevent the fine coal and ashes from getting into the interior of the fire-pot and at the same time permit a jet of air to pass over the fire to assist in the combustion of the fuel.

The base-plate 10 is preferably provided outside of the fire-pot with openings 46, one upon each side of the same, over which are arranged the covers 47. By removing these covers the soot and ashes that collect on the air-tubes 29 and the base-plate 10 may be brushed down and caused to fall through the opening into the ash-pit.

The sides of the fire-pot 41 abut against the front plate 23 on each side of the large opening provided therein, and I prefer to provide

an inclined plate 49, extending from the lower edge of the door-opening to the front edge of the grate 12. The lower end of said inclined plate bears against the beveled lower edge of the forward end of the fire-pot and is bolted to suitable ears or flanges provided upon the outer edge of the same. With this arrangement I do not need to make any provisions for dumping the grate, as in case the fire goes out or it is desired for any purpose to remove the fuel or clinkers from the fire-pot an ordinary shovel may be employed, and all of the fuel can be quickly shoveled out through the fuel-door.

15 For the purpose of supplying cold air into the furnace I provide a suitable cold-air flue or pipe 50, preferably extending directly under the furnace and provided with the open end 51, arranged directly beneath the lower ends of the air-tubes 29, as shown in Fig. 1. I may also provide a return-pipe 52, extending, for example, from the hall of the house to be heated and leading into the outer casing beneath the lower end of the drum. This 20 return-pipe is for the purpose of taking cold air from the hall in houses that are not properly ventilated. I also arrange in each of the air-tubes 29 a spirally-coiled wire 53. This coil, preferably of ordinary iron wire, is 25 shorter than the air-tube, so as not to obstruct the opening in the lower end of the same, and lies loosely against the inner wall of the tube, as shown in Fig. 2. The wire is preferably coiled so that the lower end of the spiral is 30 smaller than its upper end, and the coil is supported in the air-tube by any suitable means. This wire becomes highly heated from being in contact with the wall of the air-tube and very largely increases the radiating-surface 35 of the tube. The air passing through the tube comes in contact with the surface of the wire and, being slightly retarded by being compelled to pass over the same, becomes very highly heated before it emerges from the upper end of the air-tube.

40 I provide the straps 56 to support the horizontal smoke-pipe 32, said straps being connected at one end to said pipes, while the opposite end is hooked over the upper end of the drums 26.

45 The outer casing 54 of the furnace is preferably formed of sheet metal and is provided with the usual openings 55, to which the hot-air pipes leading to the rooms to be heated are connected. From the foregoing description it will be noted that this furnace is extremely simple and cheap in construction. The inclined air-tubes are arranged over the fire-pot, and as the products of combustion 50 must pass between and around them they will become highly heated even though only a small fire is maintained on the grate. In very large furnaces another row of air-tubes may be added, and where wood is used for fuel no difficulty at all will be experienced in heating the tubes that are some little distance from the fire. With the grate and fire-pot here

shown I may burn either hard or soft coal, lignite, or wood. The openings in the inner wall of the fire-pot will supply sufficient heated air directly over the fire to produce a substantially complete combustion of the gases. 70

As heretofore described, the smoke-pipe 32 and the air-tubes are easily accessible for cleaning purposes, so that the furnace can be 75 quickly and thoroughly cleaned from all the soot and ashes that may accumulate in it from time to time. By closing the dampers provided in the horizontal smoke-pipes 32 the fire may be kept for a long time, the smoke 80 passing out through the round holes provided in the middle of the dampers, as shown in Fig. 2.

Having thus described my invention, I claim as new and desire to secure by Letters 85 Patent—

1. In a furnace, the combination with the grate, of the drums arranged above the same, each drum comprising heads and a series of air-tubes connecting the same, and being open 90 on one side to permit the products of combustion to pass around said tubes, spirally-coiled wires within said air-tubes, and smoke-outlets provided in the walls of said drums, for the purpose set forth. 95

2. In a furnace, the combination, with the grate, of the inclined drums above the same, each drum comprising a head and a series of tubes connecting the same, smoke inlets and outlets provided in the walls of said drums 100 and coiled wires suspended within said tubes and resting against the inner walls of the same, for the purpose set forth.

3. The combination, in a furnace, with the base-plate, of the inclined drums supported 105 thereon, triangular plates secured to said base-plate and said drums, and forming with the same the inner casing of the furnace, said drums comprising a series of tubes and being open on the side next to the fire, to permit 110 the products of combustion to pass around said tubes, and the smoke-outlets provided in the walls of said drums, for the purpose set forth.

4. In a furnace, the combination, with the 115 base-plate and the side and rear walls of the ash-pit supporting the same, of the converging drums supported upon said base-plate and comprising a series of tubes and heads therefor, the grate and fire-pot also supported 120 by said base-plate, said drums being open upon one side to permit the products of combustion to pass freely around said tubes, and outlet-openings provided in the outer walls of said drums. 125

5. A furnace, comprising an inner and outer casing, a grate and fire-pot, drums within said inner casing, comprising heads and a series of tubes connecting the same, wires coiled within said tubes and inlet and outlet openings in the walls of said drums, for the purpose set forth. 130

6. In a furnace, the combination, of the base-plate forming the top of the ash-pit, the

grate supported thereby, the drums above said grate, said drums being provided with a series of air-tubes and being open on their inner sides, and the holes provided in said 5 base-plate beneath said air-tubes and means for covering the same, for the purpose set forth.

7. The combination in a furnace, of the grate, the fire-pot, the drums above said fire-pot, said drums comprising a series of air-tubes, the heads and the casing inclosing 10 three sides of said drums, said tubes being

open at each end to permit the free passage of air through the same, the intake-pipes for discharging cold air into said furnace beneath said drums, and the return-pipe leading into the furnace-casing beneath one of 15 said drums, for the purpose set forth.

In testimony whereof I have hereunto set my hand this 30th day of January, A. D. 1897. 20

FRANCIS PETELER.

In presence of—

A. C. PAUL,
RICHARD PAUL.
